UNITED STATES PATENT OFFICE

160,189

CAMERA CASE

Frank Lustig, Chicago, Ill., assignor to Revere Camera Company, Chicago, Ill., a corporation of Delaware

Application April 10, 1950, Serial No. 9,104

Term of patent 14 years

(CL. D61—1)

To all whom it may concern:

Be it known that I, Frank Lustig, a citizen of the United States, residing at Chicago, State of Illinois, have invented a new, original, and ornamental Design for a Camera Case, of which the following is a specification, reference being had to the accompanying drawings forming a part hereof.

Fig. 1 is a perspective view of a camera case showing my new design;

Fig. 2 is a front elevation thereof; the rear elevation being substantially identical thereof;

Fig. 3 is a side elevation thereof; the other side elevation being substantially identical thereto;

Fig. 4 is a top view thereof; and

Fig. 5 is a bottom view thereof.

The essential features of my design reside in the parts shown in full lines, the broken lines shown in Figs. 1, 2 and 3 merely illustrate a carrying strip of indeterminate length and have been omitted from Figs. 4 and 5 for convenience of illustration.

I claim:

The ornamental design for a camera case, as shown and described.

FRANK LUSTIG.
